UNITED STATES PATENT OFFICE.

DIEUDONNÉ TINLOT, OF NESSONVAUX, NEAR LIEGE, BELGIUM.

ELECTRICAL SWITCH.

Application filed April 4, 1922. Serial No. 549,644.

To all whom it may concern:

Be it known that I, DIEUDONNÉ TINLOT, a subject of the King of Belgium, residing at Nessonvaux, near Liege, Belgium, have 5 invented certain new and useful Improvements in Electrical Switches, of which the following is a specification, reference being had therein to the accompanying drawing.

This invention relates to electrical switches 10 and has for its object to provide an electrical switch comprising a minimum number of parts, these parts being simple, strong and adapted for mechanical production, and affording a device of economical construction 15 presenting in addition the usual facility for installation without in any way detracting from the fulfilment of the purely electrical desiderata.

The improved switch is characterized by 20 the fact that the base, which may be of any suitable material, is provided concentrically in series with projections of triangular or other shape so as to constitute a species of teeth with inclined lateral faces, between 25 which are formed suitable gaps or spaces adapted to receive the contact members.

The accompanying drawings represent by 30 way of example an electrical switch of the single pole type, but it will be understood that all desirable combinations of making and breaking the electric circuit can be obtained by the method of operation of the electrical switch which forms the subject of the invention.

35 Figure 1 represents an elevation of the single-pole switch.

Figure 2 is a plan in section on the line A—B of Figure 1.

Figure 3 shows the elevation and plan of 40 the supporting base proper, made of any suitable insulating material.

Figure 4 represents details of the operating knob or button.

Figure 5 illustrates the turning member.

45 Figure 6 comprises three detail views of one contact plate.

Figure 7 represents in detail a bridge or bar for short-circuiting the contact plates.

50 Figure 8 shows the central post or spindle of the switch, with a detail of its retaining means.

The switch illustrated comprises a base 1 made from any suitable insulating material. Upon this base 1 is placed the cover 2, preferably of insulating material, or of 55 metal lined internally with insulation. A lug or projection 3 prevents the rotation of the cover 2, which is retained in place by the operating knob 4 as hereafter explained.

Upon the upper face of the base 1 there are arranged concentrically in series projections 5 of suitable width and preferably of triangular or like shape. The apical edges of these projections, and also the intersection of the connecting surfaces with the flat part of the base 1, are aligned towards the geometrical centre of the base 1. Between these projections 5 are placed the contact plates, each comprising for example a plate 6, secured at 7 by a screw to the 70 base 1, and provided at 8 with a lug or attachment for the coupling screw of the wire or cable; the plate is continued at 9 towards the centre, then turned upwards at 12 to match the inclination of one of the faces of 75 the projections 5, upon which it rests; see Figures 1, 2 and 6.

A connecting bridge or short-circuiting bar 10, rotatable as hereafter explained, has its ends 11 shaped like spoons with suitable 80 profile so as to rest either in the gaps between the side faces of the projections 5 integral with the base 1, which position provides the opening of the electrical circuit, or in the alternate gaps of which one side 85 face is neatly covered by the correspondingly inclined extension 12 of the part 9 of the contact plate 6, in which position the circuit is closed.

In order to produce the switching movement, a post or the like 13, (see Figure 3), secured at its lower end to the base 1 and passing through the bridge part 10, is provided with a throat 14 to receive a washer piece 15 of horse-shoe shape, against which 90 there is pressed a stirrup or turning member 16 also traversed by the post or the like 13. By means of a coiled spring 17, which presses at one end upon the upper face 18 of bridge-piece 10, and at the other upon 100 the inner face of the stirrup or turning member 16, the bridge 10 is constantly

pressed down either upon the contact plates 6 or upon the insulating base, according to its position.

In order to effect the turning of the bridge-piece 10, the operating knob 4 is provided with a recessed bore 20 of square or rectangular section, fitting upon the upper narrowed portion 21 of the stirrup or turning member 16, the ends or arms 22 of which 10 are adapted to engage at 23 with the bridge-piece 10 (see Figure 2) during the rotation of the knob 4. Such movement produces firstly the turning of the bridge 10 by the engagement of the parts 22 and 23, and then 15 a sliding of the extremities 11 of the bridge over the faces of the projections 5, these faces being conductors or not, according to the arrangement of the contact plates 6.

It follows, therefore, that the bridge-piece 20 in its turning movement rises up to the top edges of the projections, compressing the spring 17, which in expanding causes the bridge-piece 10 to slide down the next faces of the projections, so that the spoon-shaped 25 ends 11 come into the next position, either in contact with the plates 6 or in the interrupted position.

The operating knob 4 rotates upon the post or the like 13 and is retained thereon by 30 a screw or nut 24.

A shoulder 25 upon the knob 4 holds the cover 2 in position in engagement with the lug 3.

The invention thus provides a simple and 35 robust switch which can be turned in either direction with a quick-break action, and adaptable to receive the necessary number of contacts and projections to form the various kinds of electrical switch required for 40 electrical installation.

What I claim and desire to secure by Letters Patent is:

1. An electric switch comprising a base having a circular series of projections disposed on the upper surface thereof, each of 45 said projections having its upper faces inclined downwardly from a central point thereof and said projections being equally spaced around a center, a pair of contact plates secured to said base having their free ends overlying the diametrically opposed inclined faces of a pair of said projections, a post coaxial with said projections extending upwardly from said base, a knob rotatable 50 on the upper end of said post, a bridging plate rotatable and slidable on said post having its free ends disposed to engage the inclined faces of said projections and said overlying contact plates, an operating member 55 detachably secured to said knob and comprising a depending arm adapted to engage a side of said bridging member, and a coil spring surrounding said post and bearing 60 at its lower end against said bridging member.

2. An electric switch comprising a base having a circular series of projections disposed on the upper surface thereof, each of said projections having its upper faces inclined downwardly from a central point 70 thereof and said projections being equally spaced around a center, a pair of contact plates secured to said base extending between the projections and having their free ends overlying the diametrically opposed faces of a pair of said projections, a post coaxial with said projections extending upwardly from said base, a knob rotatable on the upper end of said post, a bridging plate rotatable and slidable on said post having 75 its ends disposed to contact the inclined faces of said projections and said overlying contact plates, said knob having a non-circular recess in its lower end, an operating member rotatable on said post and fitting 80 said recess so as to rotate with said knob, said operating member comprising a pair of depending arms adapted to engage the sides of said bridging plate, and a coil spring surrounding said post and bearing at its ends 85 against said operating member and said bridging plate.

3. An electric switch comprising a base having a circular series of projections disposed on the upper surface thereof, each of 90 said projections having upper faces inclined downwardly from a central point thereof and said projections being equally spaced around a center, a pair of contact plates secured to said base and extending 100 into the diametrically opposite spaces between projections, a post coaxial with said projections fixed to said base and extending upwardly therefrom, a knob rotatable on the upper end of said post, a bridging plate rotatable and slidable on said post and having 105 its ends disposed to engage said projections and contact plates, an arm rotating with said knob adapted to engage said bridging plate, and a coil spring surrounding said post and bearing at its lower end against said bridging plate.

4. An electric switch comprising a base having a circular series of projections disposed on the upper surface thereof, each of 110 said projections having upper faces inclined downwardly from a central point thereof and said projections being equally spaced around a center, a pair of contact plates secured to said base and extending 115 into diametrically opposite spaces between projections, a post coaxial with said projections fixed to said base and extending upwardly therefrom, a bridging plate rotatable and slidable on said post, a knob rotatably mounted on the upper end of said post having a polygonal recess in its lower end, a yoke rotatable on said post and engaged in said recess and having depending 120 ends disposed to contact the sides of said 130

bridging plate, a coil spring surrounding said post and bearing against said bridging plate and yoke, and a cover having a central aperture through which said knob projects, said knob having an annular shoulder engaging the margin of said aperture to hold said cover in place.

In testimony whereof I hereunto affix my signature.

DIEUDONNÉ TINLOT.
